CLAIM

The ornamental design for a dispenser and display device, as shown and described.

DESCRIPTION

FIG. 1 is a perspective view of a dispenser and display device showing my design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken line showing of the aperture, latches, arms and frame is for the purpose of illustrating portions of the dispenser and display device and forms no part of the claimed design.
